TUNNEL LINER SEGMENT

Charles B. CUSHWA, Youngstown, Ohio, assignor to The Commercial Shearing & Stamping Company, Youngstown, Ohio, a corporation of Ohio

Original application December 13, 1933, Serial No. 702,188. Divided and this application September 20, 1935, Serial No. 41,435

1 Claim. (Cl. 61—45)

My invention relates to linings for earth borings and, in particular, to fabricated linings having greater strength than such structures as known heretofore.

5 This is a division of my copending application Serial No. 702,188, filed December 13, 1933, for Tunnel liners, now Patent No. 2,046,727, granted July 7, 1936.

Linings for earth borings, for example, tunnels, as usually constructed, include a plurality of rings disposed side by side and secured together, each ring being formed of an assembly of segments. The loads sustained by such linings are not uniform as to distribution or direction and this fact makes it essential that the lining have great strength in order to withstand the loads which may be concentrated at any particular area. While numerous types of segments for linings have previously been proposed, practically all of them with which I am familiar have been characterized by weak points. One of the points of greatest weakness in prior structures has been the fact that many of them rely on bent-up flanges to transmit circumferentially of the lining from one segment to its neighbors, the radial force which may happen to be concentrated thereon. It is obvious that a bent flange has a very low resistance to further bending and is, therefore, a highly inefficient means for transmitting radial thrusts from one segment to adjacent segments.

I have invented a novel form of pressed steel segment from which tunnel linings may be assembled. The segment of my invention is characterized by great strength circumferentially of a completed lining ring for transmitting stresses applied radially of the completed lining. The segments, furthermore, are very rigid throughout their length. An embodiment of the invention is shown in the accompanying drawing, together with a modification thereof, although the drawing is merely illustrative and does not represent the only forms in which the invention may be incorporated. In the drawing:

45 Figure 1 is a plan view of a segment according to my invention;

Figure 2 is a side elevation thereof;

Figure 3 is an end view;

Figure 4 is a sectional view along the line

50 IV—IV of Figure 1;

Figure 5 is a view similar to Figure 1 showing a modified form of the invention;

Figure 6 is a side elevation thereof;

Figure 7 is an end view; and

55 Figure 8 is a sectional view along the line VIII—VIII of Figure 5.

Referring in detail to the drawing, and for the present, to Figures 1 through 4 particularly, a

segment 10 is shaped by pressing, drawing, or otherwise, from a single plate. The side and end edges of the plate are bent downwardly to form side flanges 11 and end flanges 12. A stiffening rib 13 is formed adjacent the center of the web portion 14 of the segment, i. e., the portion between the side and end flanges. The rib 13 is formed by slitting the web portion 14 adjacent the end flanges, as shown at 15, and pressing inwardly the web material between the slits. The rib 13, of course, greatly increases the rigidity of the segment lengthwise, as compared to a segment without the rib.

Figures 5 through 8 show another form of segment indicated at 20. The segment 20 is pressed from a single plate like the segment 10 but has separately formed end walls 21. The web of the segment 20 is bent to form side flanges 22. The intermediate portions of the web are doubled back on themselves to form ribs or plaits 23 extending longitudinally of the segment. The end walls 21 are attached to the ends of the segment by welding. It will be apparent that the lengthwise rigidity and strength of the segment of Figures 5 through 8 are even greater than those of the segment of Figures 1 through 4. The number of ribs 23 may be varied to suit different conditions and the longitudinal strength and rigidity of the segment will vary correspondingly. A particular advantage of the construction shown in Figures 5 through 8 is that the ribs 23 abut against the end walls 21 and therefore provide substantial support against inward bending of the end walls which might otherwise result from the circumferential forces set up by stresses radial to the completed tunnel lining.

It will be apparent from the foregoing description that my invention provides a number of forms of liner segments characterized by greater strength than those known heretofore, particularly with reference to the resistance of the segment to bending of the flanges thereof relative to the body portion.

While I have illustrated only a few possible embodiments of the invention, it will be apparent that it may be otherwise constructed than as shown and described herein without departing from the spirit of the invention or the scope of the appended claim.

I claim:

50 A liner segment comprising a plate curved along one dimension, side walls extending inwardly of the curved edges of the plate, said plate having a plait forming a strengthening rib extending inwardly of the plate to substantially the depth of said side walls and end walls welded to the ends of the side walls and of the plait.

CHARLES B. CUSHWA.
